FISHING MOTOR FOOT PEDAL CONTROL

Ralph C. Osborn, Bloomington, Ill., assignor to
Osborn Engineering Corporation

Filed Oct. 27, 1969, Ser. No. 19,746

Term of patent 7 years

Int. Cl. D13—03

U.S. Cl. D26—13

FIG. 1 is a perspective view of the fishing motor foot pedal control;

FIG. 2 is a side view;

FIG. 3 is a top view;

FIG. 4 is an end view;

FIG. 5 is a side view of a modified fishing motor foot pedal control;

FIG. 6 is a top view; and

FIG. 7 is a perspective view.

I claim:

The ornamental design for a fishing motor foot pedal control, substantially as shown and described.
